UNITED STATES PATENT OFFICE

FRANK M. ZIMMERMAN, OF AURORA, ILLINOIS

LABEL HOLDER

Application filed February 20, 1928. Serial No. 255,646.

This invention relates to label holding means, and more especially to means of moulding-like character adapted for holding labels interchangeably on display shelves, storage bins and the like, as for marking the price or the kind of goods referred to, and is an improvement relative to my Patent No. 1,600,382.

I have found that it is often difficult or impossible to make satisfactory wooden mouldings adapted for this purpose, of sufficiently narrow width to register with the thickness of the shelving which is usually about three-fourths of an inch thick, especially when the largest possible size of label consistent with the thickness of the shelf is required. Moreover some shelving is even thinner. Although sheet metal moulding has been used for holding labels, it has proven unsatisfactory mainly for the reason that it was structurally defective and resulted in injury to persons using the same, as by cutting the fingers.

The main objects of my present invention are to provide an improved form of label holder; to provide such a holder in thin and narrow elongated strip form, adapted for cutting to fit any desired lengths; to provide such mouldings of shallow channel-shape, adapted to hold a label card in flat form and in such manner as to prevent accidental endwise slipping; and to provide such a moulding adapted to permit ready insertion of the label without distortion or bending thereof, and mainly by vertical movement and wherein the label will be held in place mainly by gravity, though removable by simple inverse operation.

Illustrative embodiments of this invention are shown by the accompanying drawings in which:

Figure 1 is a vertical section through a shelving system, equipped with label holders such as herein described.

Figure 2 is an enlarged section showing in detail the upper label holder of Figure 1.

Figure 3 is mainly similar to Figure 2 but shows the label elevated somewhat for insertion or removal.

Figure 4 is an enlarged vertical section

showing in detail the lower label holder of Figure 1.

Figure 5 is an end view of a very thin molding of sheet metal having plain rounded edges.

In the construction shown in the drawings, the shelves 1 and 2 are supported on the wall 3 and are provided with labels 4 and 5 to indicate the price or character of the goods 6 and 7 displayed on said shelves.

The upper label 4 is narrow and held by a sheet metal moulding 8 corresponding in width with the thickness of its supporting shelf 1. The lower label 5 is relatively wide and is held by a wooden moulding 9 secured to its supporting shelf 2, this moulding being wider than the thickness of the shelf and extending downward sufficiently to accommodate the greater width of the label. The mouldings 8 and 9 are attached to their respective shelves by any convenient fastening 10, as for instance nails or screws.

Referring now to the details of the sheet metal moulding 8, as shown in Figure 2, this member includes a flat back part 11, bordered at its upper edge by a forwardly-bent flange 12 which is turned downwardly at 13 in front and terminates with an inclined upwardly-turned edge part 14 whereby a channel 15 is provided to receive the upper edge of the label 4. In a somewhat similar manner the lower edge of the moulding is provided with a forwardly-turned flange 16 having an upwardly-turned front part 17, terminating with a downwardly-inclined edge part 18, whereby there is provided a channel 19 to receive the lower edge of the label.

It is to be noted especially that the upper channel 15 is appreciably deeper than the lower channel 19, so as to accommodate raising the label sufficiently to release its lower edge, said channel 15 being deep enough to retain the upper edge of the label when the latter is resting normally in place. Moreover, the edge part 18 is so positioned that the bottom of channel 19, which is wedge-shape is sufficiently narrow to grip the lower edge of the label wedgingly and so prevent accidental sidewise slipping of the label. The upper channel is formed to permit full upward

movement of the label.

movement of the label without appreciable wedging and the edge part 14 is inclined sufficiently to accommodate the insertion and removal of the label without bending, as will be apparent from Figure 3.

5 Referring now to Figure 4, which shows the details of the lower moulding of Figure 1, this moulding includes a plain back part 21 having a forwardly-projecting top edge portion 22, terminating in a downward flange 23, the back edge of which is inclined as shown at 24, whereby a V-shaped channel 25 is provided to receive the upper edge of the label 5. The lower edge of the moulding 10 9 is provided with a forwardly-extending part 26, terminating in an upward flange 27, having an inclined back face 28, whereby a wedge-shaped channel 29 is provided to receive the lower edge of label 5.

15 20 It is to be noted that the upper flange 23 is deeper than the lower flange 27 and that the lower channel 29 is narrower than the upper channel 25. As a result of this construction, the label may be raised sufficiently 25 to release its lower edge but the upper edge cannot escape so long as the lower edge is in its channel 29. Here, too, endwise movement of the label is opposed by its wedging position in the narrow bottom channel.

25 30 By the construction above described, the label may be easily inserted and removed without bending or creasing and with corresponding less likelihood of soiling in such use. Furthermore, the construction of the 35 edge flanges of the metal moulding is such that it combines facility of use with safety against injury to those who have occasion to handle the moulding or who have to insert and remove labels. This safety feature is 40 accomplished by turning the sharp edge of the moulding inward, as indicated at 14 and 18 on Figure 2, where it serves also to good structural and operating advantage as well as for safety.

45 Referring to Figure 1, it is apparent that the narrow metal moulding 8 accommodates the widest possible label consistent with non-overlapping of the moulding above or below the edge of the shelf and that with such a 50 moulding a maximum economy of space is attainable, no head room above the goods being sacrificed on account of a depending moulding. However, where such economy of space is not required but rather conspicuous labels and a more pleasing finish are 55 desired, the wooden moulding, such as indicated by numeral 9, may well be used, as it presents a finer and neater appearance and is usually not much more expensive to manufacture and sell.

60 In the somewhat simplified design of Fig. 5, the card 4, indicated by dotted lines, is applied to a sheet metal holder 31 comprising a flat back part 32 with top and bottom flanges turned forwardly at 33 and 34 and

convergently at 35 and 36, but inclined outward slightly to accommodate ready insertion and removal of said card. The upper channel 37 permits the upper edge of the card to rise freely therein for manipulation in and out. The lower channel 38 is V-shaped, as at the lower edge of Fig. 4, and for like reason. The edges 39 and 40 are formed rounded and smooth by the rolling process used in manufacturing the flat stock 70 75 strips.

This Fig. 5 style of moulding has some advantages over that of Figs. 2 and 3 in that, for a given size, it can be made from somewhat narrower stock, and is a little easier to 80 mold. But on the other hand it is not so easy to obtain the desired stock of assorted widths. The strips used for Fig. 2 style is sheared to order from sheet stock, but the resultant sharp "raw" edges are dangerous unless 85 turned inward and folded back in the molding process, as in Fig. 2. The strips for Fig. 5 style have to be rolled for predetermined widths, corresponding rolls being used; and hence, on account of rolling costs 90 and rather limited general demand for such strips, practical limitations favor style Fig. 2, except where proper stock strips for style 5 can be found in the market, as for instance 95 in long rolls from which the stock may be straightened out as it runs through the molding machine, and then cut into desired lengths ready for use.

Such sheet metal molding is made of rather thin stock such as permits of attachment by 100 driving nails therethrough wherever necessary. Sheet iron is most commonly used. It may of course be finished in any desired style as, for instance, oxidized, tinned, or galvanized, et cetera.

105 It is to be noted that in all of these designs I obviate the need of a deep channel or concavely rounded bottom therefor to accommodate insertion of the cards, as this is provided for by the top and bottom grooves. Hence 110 my present moldings may all be of very shallow depth.

115 Although certain specific embodiments of this invention have been selected to illustrate my improvements herein set forth, it is to be understood that some of the details of the constructions shown may be altered or omitted without departing from the spirit of this invention as defined by the following 120 claims.

I claim:

1. A label holder comprising a molding 125 grooved on its front side to receive a label and having top and bottom flanges turned convergently to hold the edges of the label, the top flange being appreciably wider than the bottom flange, and the bottom flange having an abruptly inclined inner face whereby a V-shaped channel is provided of sufficient acuteness to wedgingly embrace the lower 130

edge of the label and prevent accidental lateral displacement thereof.

2. A shelf provided with a label detachably mounted on the front edge thereof, said shelf having a sheet metal holder secured thereto formed with top and bottom channel flanges to embrace the edges of said label, said holder being substantially equal in width to the thickness of the shelf, said label being only slightly less in width, the upper flange being wider than the lower flange and the distance from the upper edge of the lower flange to the top of the upper channel space being substantially equal to or slightly greater than the width of the label, whereby the latter may be inserted and removed by vertical movement mainly and without bending, and the lower channel being V-shaped with a sharply acute bottom part somewhat narrower than the thickness of said label, whereby accidental lateral displacement of the label is prevented.

3. A label holder comprising an integral strip of sheet metal provided on its lateral edges with convergingly turned flanges, the edge portions of said strip being positioned within said flanges and extending diagonally thereof for holding a label against the face of said strip.

4. A label holder comprising an integral strip of metal having top and bottom flanges formed thereon, each comprising an open-sided tubular structure, the top flange being appreciably wider than the bottom flange, and yieldable clamping means extending diagonally of the interior of each flange constricting the open side thereof and comprising lateral inwardly folded extremities of said strip for providing a smooth edge on each flange and for yieldably holding labels against the outer side of said strip.

Signed at Chicago this 1st day of February, 1928.

FRANK M. ZIMMERMAN.
